WATER AND OIL COOLER

James Frank Belaieff, Cricklewood, London, England, assignor of two-thirds to Cyril Terence Delaney, and Gallay, Limited, Cricklewood, London, England, a company of Great Britain

Application April 17, 1943, Serial No. 483,454
In Great Britain February 2, 1942

4 Claims. (Cl. 257—130)

This invention relates to water and oil cooler and like combined heat exchangers and more particularly to apparatus of the kind wherein provision is made in the same unit for two or more coolant mediums as for example, a combined oil cooler and water radiator.

With the orthodox type of oil cooler great difficulty has occurred in cooling the oil in a very cold or arctic condition, owing to coring phenomena which takes place in the oil circulation. By coring of oil in the oil discharge is meant the gradual thickening of the oil at the wall of the passage due to chilling, this thickening progressively moving toward the center of the passage until at last all the oil in the passage is so thick that flow is stopped.

Combined water radiators and oil coolers have been manufactured in the past but have proved very unsatisfactory owing to the fact that certain parts of the oil cooler were in direct contact with the water circulation system. In such constructions there was always the possibility of a leakage developing between the oil and water circulation which it was not possible to detect from outside.

It is also known to arrange a water radiator and oil cooler in juxtaposition so that air reaches the oil cooler after passing over the water radiator, the chief disadvantage of such an arrangement being that air reaching the oil cooler has already been heated above normal temperature.

The object of the present invention is to provide an improved combined heat exchange apparatus in which some or all of the above disadvantages are overcome.

According to the present invention the passages or the two coolant media are interdisposed in such a manner that the heat from the one can be transferred to the other or vice versa, the respective passages being at all times separated by an air space.

The air spaces may contain corrugated members and the passages may be formed by corrugated members.

In devices of this character one face of the device is cooled before the other due either to motion through a cold atmosphere or through the action of a fan in blowing relatively cool air against that face of the device. This produces a certain amount of upward flow of the material being cooled at what may be termed the front face, and a certain amount of downward flow at what may be termed the rear face. Thus there is a fore and aft flow of the material being cooled.

In order that this invention may be more clearly

understood, reference will now be made to the accompanying drawings wherein:

Fig. 1 is a front elevation of a combined oil cooler and water radiator.

Fig. 2 is a side view of the device, the water passages being shown in dotted lines.

Fig. 3 is a similar view, the oil passages being shown in dotted lines.

Fig. 4 is an enlarged detail vertical sectional view of the radiator block illustrating the construction of the water radiator units.

Fig. 5 is an enlarged detail vertical sectional view taken on the line 5—5 of Fig. 4.

Fig. 6 is an enlarged detail sectional view taken on the line 6—6 of Fig. 4.

Fig. 7 is an enlarged detail sectional view taken on the line 7—7 of Fig. 4.

The combined oil cooler and water radiator units comprise a radiator block where the oil cooler units *a* are interposed between the water radiator units *b*. The units *a* are connected to oil tanks *c* and *d*, and the water units *b* to water tanks *e* and *f*. The oil cooler units and water radiator units are held in spaced relationship by corrugated strips *g*. The thickness of the corrugated strips which form these struts will vary with the amount of heat which has to be dissipated either by water or oil. In this particular instance, the water tank is placed at one end and the oil cooler tank at the other end of the heat exchange unit.

The water tanks *e* and *f*, as clearly shown in Fig. 2, are located at the top of the device and the oil tanks *c* and *d* are located at the bottom of the device. The alternately arranged oil cooler units *a* and water radiator units *b* are spaced apart to provide intervening air spaces and the corrugated strips *g* are located in the air spaces. These units *a* and *b* are thin, as clearly shown in Fig. 1 of the drawings, and are rectangular, as illustrated in Figs. 2 and 3 of the drawings. Fore and aft passages *1* and *2* are connected by arcuate passages *3* and *4* and these passages may be formed by corrugated members.

The fore and aft passages *1*, which are contained within the water radiator units, extend downwardly from the water tanks *e* and *f* and terminate at their lower ends at a point intermediate the top and bottom of the water radiator units *b* and they are arranged in a series extending from one side edge to the other side edge of the units. The arcuate passages *3*, which register with the lower ends of the vertical passages *1*, form a series which are spaced from the side edges and bottom of the water radiator units *b*

to form intervening spaces 3 and the vertical passages at the ends of the series communicate with the space partially surrounding the series of arcuate passages.

The fore and aft or vertical passages 2 of the oil cooler units extend upwardly from the oil tanks and terminate intermediate of the top and bottom of the units, as clearly shown in Fig. 3 of the drawings, and the arcuate passages 4 of the oil cooler units form a series which are spaced from the top and side edges of the units a so that the vertical passages at the end of the series thereof communicate with the intervening space 5 between the series of arcuate passages 4 and the top and side edges of the oil cooler units a. The oil and water circulate through the passages and intervening spaces 3 and 5, as indicated by the arrows in the drawings.

With a combined water radiator and oil cooler according to the present invention no passages of the oil cooler or water radiator are in direct contact. If a leakage occurred on one of the elements the oil or water will leak outside the heat exchange unit and will easily be detected.

As the water heats up more rapidly than the oil, some heat will be transferred from the water to the oil, thus shortening the time taken in cold weather for the lubricant to reach the temperature when it can do its work efficiently.

If the oil temperature exceeds that of the water temperature some heat may be conducted to the water and so help in keeping down the temperature of the oil.

What I claim and desire to secure by Letters Patent is:

1. A combined water cooling radiator and oil cooler including a radiator block comprising water radiator units and oil cooler units spaced apart to provide intervening air spaces, a pair of water tanks arranged at the top of the radiator block, a pair of oil tanks located at the bottom of the radiator block, vertical water passages contained within the water radiator units and extending downwardly from the water tanks and terminating short of the bottoms thereof, arcuate passages registering with the lower ends of the water passages, vertical oil passages contained within the oil cooler units and extending upwardly from the bottoms thereof and terminating intermediate of the top and bottom of the same and communicating with the oil tanks, and arcuate oil passages registering with the oil passages.

2. A combined water cooling radiator and oil cooler including a radiator block comprising thin, rectangular water radiator units and thin, rectangular oil cooler units spaced apart to provide intervening air spaces, a pair of water tanks ar-

ranged at the top of the radiator block, a pair of oil tanks located at the bottom of the radiator block, vertical water passages contained within the water radiator units and extending downwardly from the water tanks and terminating short of the bottoms thereof, arcuate passages registering with the lower ends of the water passages, vertical oil passages contained within the oil cooler units and extending upwardly from the bottoms thereof and terminating intermediate of the top and bottom of the same and communicating with the oil tanks, and arcuate oil passages registering with the oil passages.

3. A combined water cooling radiator and oil cooler including a radiator block comprising water radiator units and oil cooler units spaced apart to provide intervening air spaces, a pair of water tanks arranged at the top of the radiator block, a pair of oil tanks located at the bottom of the radiator block, vertical water passages contained within the water radiator units and extending downwardly from the water tanks and terminating short of the bottoms thereof, arcuate passages registering with the lower ends of the water passages, vertical oil passages contained within the oil cooler units and extending upwardly from the bottoms thereof and terminating intermediate of the top and bottom of the same and communicating with the oil tanks, and arcuate oil passages registering with the oil passages.

4. A combined water cooling radiator and oil cooler including a radiator block comprising thin, rectangular water radiator units and thin, rectangular oil cooler units spaced apart to provide intervening air spaces, a pair of water tanks arranged at the top of the radiator block, a pair of oil tanks located at the bottom of the radiator block, vertical water passages contained within the water radiator units and extending downwardly from the water tanks and terminating short of the bottoms thereof, arcuate passages registering with the lower ends of the water passages, vertical oil passages contained within the oil cooler units and extending upwardly from the bottoms thereof and terminating intermediate of the top and bottom of the same and communicating with the oil tanks, and arcuate oil passages registering with the oil passages, said series of arcuate passages being spaced from the walls of their respective units to provide intervening spaces and certain of the vertical passages communicating with said intervening spaces.

5. A combined water cooling radiator and oil cooler including a radiator block comprising thin, rectangular water radiator units and thin, rectangular oil cooler units spaced apart to provide intervening air spaces, a pair of water tanks ar-

anged at the top of the radiator block, a pair of oil tanks located at the bottom of the radiator block, vertical water passages contained within the water radiator units and extending downwardly from the water tanks and terminating short of the bottoms thereof, arcuate passages registering with the lower ends of the water passages, vertical oil passages contained within the oil cooler units and extending upwardly from the bottoms thereof and terminating intermediate of the top and bottom of the same and communicating with the oil tanks, and arcuate oil passages registering with the oil passages, said series of arcuate passages being spaced from the walls of their respective units to provide intervening spaces and certain of the vertical passages communicating with said intervening spaces.

JAMES FRANK BELAIEFF.
